UNITED STATES PATENT OFFICE.

VICTOR H. CANHAM, OF BUFFALO, NEW YORK.

GARMENT HANGER.

Application filed February 24, 1922. Serial No. 538,903.

To all whom it may concern:

Be it known that I, VICTOR H. CANHAM, a citizen of the United States, residing at Buffalo, in the county of Erie and State of New York, have invented new and useful Improvements in Garment Hangers, of which the following is a specification.

This invention relates to a hanger or support for garments, and its chief object is to provide a hanger of improved construction which enables a coat or similar garment to be suspended without sagging at the collar, and which can be manufactured at a moderate cost.

Another object of the invention is to provide the hanger with a simple detachable support for trousers and the like.

In the accompanying drawings:

Figure 1 is a perspective view of the device taken from its front side. Figure 2 is a fragmentary rear view thereof, partly in section. Figure 3 is a horizontal section on line 3—3, Fig. 2. Figure 4 is a top plan view of one of the blanks from which the shoulder-wings are formed. Figure 5 is a perspective view of a modified form of the name plate.

Similar characters of reference indicate corresponding parts throughout the several views.

The main body or frame of the hanger is preferably of skeleton-like form and constructed of a single piece of wire including a base portion or member 10, rearwardly extending end portions 11, and an arched or upwardly-curved shoulder portion or member 12. The free inner ends or branches 13 of the base portion are bent rearwardly at a point substantially midway of its length and are joined together by twisting or otherwise, as shown in Figs. 1 and 2. One of these branches is comparatively long and is bent upwardly to form a post or upright supporting member 13^a which extends above the shoulder portion 12 and terminates in a suspension hook 14. Below this hook, the post is provided with a rearwardly-offset loop 15 which embraces the adjacent central part of the shoulder portion 12, reliably interlocking these parts and preventing displacement thereof.

Arranged on either side of the post 13 and at a distance from the end bars 11, are shoulder-wings or forms 16, 16, which connect the shoulder portion 12 with the base portion 10. These wings are preferably con-

structed of sheet metal and are attached at their ends to said parts by bending or curling them around the same. The side edges of each wing are substantially parallel and straight, while its lower attaching end is horizontal and its upper attaching end is oblique or arranged at an angle to conform to the arched portion 12, as shown in Fig. 4, producing a comparatively low or short outer edge and a comparatively high or long inner edge. As shown in Figs. 1 and 2, these wings extend upwardly from the base portion of the hanger and are thence curved rearwardly to the oppositely inclined shoulder portions.

By this construction, the wings are bent to the proper curvature to cause the collar and adjoining parts of the coat to lie smoothly thereon without permitting sagging of the collar. Furthermore, by shaping the wings in this manner, a saving in material is effected, as they can be cut from a parallel-edged strip or blank such as shown in Fig. 4, entailing practically no waste.

17 represents a name plate disposed between the lower portions of the shoulder wings and provided at its ends with inwardly facing guide flanges 18 which interlock with corresponding outwardly-facing flanges or guideways 19 formed along the inner upright edges of said wings, as shown in Figs. 2 and 3. The corners at the opposite lower ends of the plate may be cut off, as shown in Fig. 2, to enable the latter to be positioned close to the base of the garment frame.

Detachably suspended from the base portion 10 of the hanger is a trouser-support 20 which is preferably of substantially U-shaped form and constructed of wire. The upper ends of the arms 20^a of this support are bent or offset rearwardly, as shown at 21, and terminate in inwardly-facing hooks 22. The distance between these arms is substantially the same as that between the corresponding outer edges of the shoulder wings 16. In applying the trouser support to the coat-hanger, one of its arms is placed against the front side of the base portion 10 with its hook engaging behind the adjacent shoulder wing, and the hook of the other arm is then sprung behind the corresponding shoulder wing. By providing the offsets 21, the trouser support is allowed to hang in a vertical position, being prevented from swinging rearwardly by the hooks which

abut against the rear sides of the shoulder-wings.

In the modification of the name plate shown in Fig. 5, the same is provided near 5 its ends with inwardly-facing guide lips 18^a which are formed by producing U-shaped slits in said plate and then punching the resulting tongues outwardly.

I claim as my invention:

10 1. A garment hanger, comprising a horizontal base member, an arched shoulder member offset rearwardly from said base member and extending above the same, and sheet-metal shoulder-strips connecting said 15 base member with said shoulder member and having substantially straight and paral-

lel side edges, the upper ends of said strips being oblique and curled around said shoulder member and the lower ends of the strips being horizontal and curled around said base member. 20

2. A garment hanger, comprising a base portion, a shoulder portion, shoulder wings connecting said base portion with said shoulder portion, and a U-shaped trouser support hung from said base portion, the arms of said support being offset rearwardly near their upper ends and terminating in inwardly-facing suspension hooks which engage behind said wings. 25

VICTOR H. CANHAM.
